UNITED STATES PATENT OFFICE.

DAVID D. GORDON, OF CHICAGO, ILLINOIS, ASSIGNOR TO ECONOMY FUSE & MANUFACTURING CO., OF CHICAGO, ILLINOIS, A CORPORATION OF NEW YORK.

SWITCH MOUNTING.

Application filed January 31, 1925. Serial No. 5,915.

The present invention relates to switch mountings.

More particularly the present invention relates to electric light fixtures and is particularly useful in connection with the type of socket known as a candle socket, though as the description proceeds it will be apparent that the invention is of broader application. The invention will be described with reference 10 to the type of socket known as candle socket in order that conciseness and definiteness of description may be had.

An object of the present invention is to provide a switch mounting which may be 15 readily assembled and which in the case of a lamp socket having a flexible operating member will permit said operating member to assume the position to which it is biased by gravity.

20 A further object is to provide conveniently operated means for controlling the position of an electric light socket in a direction axially of its length.

25 A further object is to provide lamp socket means which is readily adjustable either axially or circumferentially and which will remain securely in adjusted position.

30 A further object is to provide lamp socket means of the candle type which in cases where a pull chain or cord control is used will permit said chain or cord to assume the position which it will tend to assume through the influence of gravity.

35 A further object is to provide a socket supporting member readily adjustable for different lengths of candle simulating means.

Further objects will appear as the description proceeds.

Referring to the drawings—

40 Figure 1 is a longitudinal sectional view of one embodiment of the present invention;

Figure 2 is a transverse sectional view taken along the plane indicated by the arrows 2—2 of Figure 1;

45 Figure 3 is a fragmentary view in longitudinal section of a modified embodiment of the present invention;

Figure 4 is a transverse sectional view taken along the plane indicated by the arrows 4—4 of Figure 3;

50 Figure 5 is a fragmentary sectional view illustrating another embodiment of the present invention;

Figure 6 is a transverse sectional view taken along the plane indicated by the arrows 6—6 of Figure 5;

Figure 7 is a fragmentary transverse sectional view showing still another modification; and

Figure 8 is a view of a fixture of a type in common use to which the present invention is particularly applicable.

Referring to Figure 1, the numeral 10 indicates a conduit for the electric wires 11—11, which wires are shown broken away but which, as is well known, will be connected to the two terminals of an electric socket, an example of an electric socket being indicated by the numeral 12. Said socket 12 is shown as holding an electric lamp 13. According to the disclosures of Figures 1, 3 and 5, the conduit 10 has mounted thereon the holder 14, which has swedged thereto the collar 15, which collar 15 is provided with the set screw 16, whereby said collar 15 and holder 14 may be held in position on the conduit 10. The holder 14 is adapted to receive and hold the sleeve 17 which houses the socket 12, together with the means for controlling said socket and for supporting said socket. The sleeve 17 may be white or colored, to simulate a candle. According to the embodiment illustrated in Figure 1, a ratchet mechanism is provided for opening and closing the electric circuit through the electric lamp 13, which ratchet 85 mechanism is indicated as a whole by the numeral 18. A pendant operating member 19, preferably flexible, is provided for operating the ratchet 18. As is well known, alternate pulls on the member 19 will open and close the electric circuit of the wires 11—11 through the electric lamp 13. The holder 14 is provided with the aperture 20 to permit the passage therethrough of the operating member 19. It will be obvious, of course that in order to avoid sticking of the operating member 19, said member should hang naturally, in such a position as to be clear of the wall of the aperture 20. By reason of the present invention this advantage may be accomplished without any particular skill on the part of the person mounting the electric socket in place.

Projecting downwardly from the socket 12 is the stud 21. Mounted upon the conduit 10 is the collar 22, which may be held in place by means of a set screw 23. The collar 22

- is provided with a pair of upstanding arms 24—24 adapted to embrace the downwardly extending stud of the socket 12. Encircling the arms 24—24 is the ring 25. The downwardly extending stud 21 will be of sufficient size so that when it is lying between the arms 24—24 it will tend to spring said arms outwardly to a small extent to cause the outside walls of said arms to assume a slight taper. 5 It will be clear that by pushing up upon the ring 25, when the stud 21 is in place between the arms 24—24, a gripping action will be had upon said stud, whereby said stud, and consequently said socket 12, will be held securely against either axial movement or rotative movement. 10

- According to the structure illustrated in Figures 3 and 4, the stud 21 is exteriorly screw-threaded and the arms 24—24 have an 20 interiorly screw-threaded portion engaging with the screw-threads on said stud 21. According to this embodiment, also, when the stud 21 is turned down into screw-threaded engagement with the arms 24—24 said arms 25 will be sprung apart slightly, whereby the exterior walls are tapered. When the sleeve 25 is slid upwardly upon said arms 24—24 a very firm engagement is had, preventing movement of the stud 21. 30 According to the structure illustrated in Figures 5 and 6, the stud 21 has a smooth exterior and the arms 24—24 are exteriorly screw-threaded. In this case the sleeve 25 is interiorly screw-threaded. In this case as 35 in the constructions illustrated in Figures 1, 2, 3 and 4, the arms 24—24 will be sprung apart slightly when the stud 21 is thrust between said arms, whereby when the sleeve 28 is turned upwardly on the arms 24—24 a firm gripping action is had between said arms and said stud 21. 40

- According to the embodiment shown in Figure 7, the sleeve 25 is provided with a set screw 26 adapted to engage one of the arms 45 24—24. According to the structure shown in Figure 7, the stud 21 may be mounted in proper position between the arms 24, after which the set screw 26 will be screwed in to hold the stud 21 firmly against movement 50 relative to the arms 24—24.

- It will be understood, of course, that in each of the embodiments of the present invention above described adjustment of the stud 21 and sleeve 25 will be had while the ornamental 55 sleeve 17 is out of obstructing relationship therewith, it being a simple matter to slip the sleeve 17 into place after the proper adjustment has been accomplished.

- In practice sleeves of a variety of lengths 60 are used. According to the present invention sleeves of a wide variety of lengths may be accommodated by a single design of the mechanism embodying the present invention. By reason of the adjustable means for holding the socket 12 the advantage is at-

tained, therefore, that the number of parts to be stocked for different lengths of sleeve 17 will be minimized. Not only is the advantage attained that the elevation of the socket may be readily changed to correspond to the 70 height of the sleeve 17 being used, but the further advantage is attained that the ratchet mechanism 18 and the operating member 19 may be so disposed that the operating member will fall naturally through the hole 20 75 provided for said member. This latter feature is important for the reason that the member 19 should lie in a position in which it may be readily grasped by a person desiring to operate same. In the non-adjustable 80 socket holders as heretofore provided it frequently happens that in order to have the end of the operating member in a position to be conveniently grasped the socket 14 must be mounted on the conduit 10 in such a position that said operating member is twisted 85 intermediate of its length. In structures such as shown in Figure 8, which variety of structure is in common use, the holder portion 14 is fixedly connected to the stem 27, which stem 90 95 27 is fixedly mounted relative to a supporting member, such as a wall, 28. The present invention presents decided advantages in connection with the type of bracket shown in Figure 8, inasmuch as the fact that the ratchet mechanism is adjustable rotatively carries with it the advantage that the operating member 19 may fall naturally through the hole 20.

Though certain preferred embodiments of the present invention have been described in detail, it will be clear that many modifications will occur to those skilled in the art. It is intended to cover all such modifications that fall within the scope of the appended 100 105 claims.

What is claimed is:

1. In lamp socket mechanism, a conduit for electric wires, elongated holding means mounted on said conduit, an electric socket, a stem carried by said socket said stem having a smooth cylindrical portion adapted to be located between said holding means and having a rotary and axially slideable bearing relationship therewith, and ring means encircling said holding means for holding same in gripping relationship with said stem, said holding means being adapted to be freed sufficiently from said stem to permit longitudinal sliding movement of said stem between said holding means independently of any rotative movement of said stem. 110 115 120

2. In a candle socket, a candle cup, a candle sleeve, an electric socket within said sleeve, ratchet mechanism for controlling said socket, elongated holding means, a smooth cylindrical stem for supporting said socket and said ratchet mechanism, a pendant member for operating said ratchet mechanism, said candle cup being provided with a hole for permitting the passage therethrough of 125 130

said pendant member, and ring means co-operating with said holding means for holding said stem in adjusted position both rotatably and longitudinally relative to said holding means, said holding means being adapted to be freed sufficiently from said stem to permit longitudinal sliding adjusting

movement of said stem relative to said holding means independently of any rotative movement of said stem.

Signed at Chicago, Illinois, this 29th day of January, 1925.

DAVID D. GORDON.
